RUDOLF HENRIK KJELLMAN AND GUSTAF LEANDER ANDERSSON, OF STOCKHOLM, SWEDEN, ASSIGNORS TO AKTIEBOLAGET AUTOMATGEVAR, OF SAME PLACE.

MAGAZINE-CLOSURE FOR FIREARMS.

SPECIFICATION forming part of Letters Patent No. 672,783, dated April 23, 1901.

Application filed January 17, 1901. Serial No. 43,591. (No model.)

To all whom it may concern:

Be it known that we, RUDOLF HENRIK KJELLMAN, director, and GUSTAF LEANDER ANDERSSON, mechanician, subjects of the King of Sweden and Norway, and residents of Handverkaregatan 37, Stockholm, in the Kingdom of Sweden, have invented certain new and useful Improvements in Firearms, (for which we filed applications for patents in 5 Sweden on the 27th day of September, 1900, under No. 1,591; in Norway on the 19th day of October, 1900, under No. 13,081; in Denmark on the 19th day of October, 1900, under No. 1,119; in Germany on the 24th day of October, 1900, under No. A 7,474, 111/72^a; in Austria on the 22d day of October, 1900; in Hungary on the 25th day of October, 1900, under No. 14,930; in Switzerland on the 23d day of October, 1900, under No. 25,145; in 10 France on the 10th day of November, 1900, under No. 293,655; in Belgium on the 27th day of October, 1900, under No. 121,017; in Italy on the 13th day of November, 1900, under No. 15,920; in Finland on the 16th day 15 of November, 1900; in Spain on the 13th day of November, 1900; in Russia on the 7/20 day of November, 1900, under No. 12,530, and in Turkey on the 22d day of November, 1900, under No. 500/476,) of which the following 20 is a specification, reference being had there- 25 in to the accompanying drawings.

This invention relates to improvements in firearms with a view to effecting an easy insertion of the cartridge-carrier into the cartridge-box as well as its ready removal from the latter.

Figure 1 shows a longitudinal section of the cartridge-box with the cartridge-carrier placed therein, and Fig. 2 a transverse section of the same on line *a b* of Fig. 1. Fig. 3 shows the cartridge-box viewed from below, and Fig. 4 the cartridge-carrier viewed from below with its supporting-springs partly cut away.

The carrier 1 is supported by two crossed or otherwise suitably placed shaped springs 2 2, projecting from each end of a bottom piece 3 and attached at opposite ends of the

carrier. The piece 3, which may be made in one piece with the springs, the latter being 50 folded over the former, or to which the springs may be specially attached, engages with its ends in grooves 4 or in notches or between lugs or the like on the end walls of the cartridge-box 5, and its length is so gaged that 55 it forms an inwardly-curved arc, thus forming a spring, which is kept in a state of tension between the ends of the box. If one end of the spring 3 is pressed into the box by one finger, as indicated by dotted lines, the other 60 end of the spring thereby will become disengaged from the box and drop out of the latter, it being afterward easy to remove parts 1, 2, and 3 from the box. When they are to be inserted, the carrier is put in first, then one 65 end of spring 3 is inserted into the recess provided for it in the box, and, finally, the other end of the spring 3 is pushed into the recess at the other end of the box. Against pressure acting from above the spring 3 rests perfectly secure in the box 5; but from below it can be readily disengaged by the simple manipulation described. The spring 2 3 and the carrier can also be easily disengaged from each other. For this purpose one spring end 70 6 is shaped as a hook and inserted through an eye or loop 7 on the carrier, and the other spring end 8 is provided with a slot 9 larger at one end, so as to admit of the said spring end being slipped onto a stud 10, secured to 75 the carrier 1 and provided with a head. When the spring is to be disengaged, one of its ends 8 is first unhooked from the stud 10, and the spring is subsequently swung into the dotted position, Fig. 4, and finally unhooked from 80 the eye 7. The slot 9 permits a shifting of the spring on the stud in its usual yielding action as the carrier rises and descends.

Having now described our invention, what we claim as new, and desire to secure by Letters Patent, is—

In combination with firearms, a springing bottom part 3 forming support for the spring or springs serving to elevate the cartridge-carrier, said bottom part spanning in an arc 95 the distance between the end walls of the

cartridge-box and its ends engaging with recesses or notches in the said walls, from which it can be unhooked by applying a pressure upon it from below, or into which it can be inserted from below, all with a view to accomplishing a ready insertion and removal of the springs and cartridge-carrier.

5 In witness whereof we have hereunto signed

our names in the presence of two subscribing witnesses.

RUDOLF HENRIK KJELLMAN.
GUSTAF LEANDER ANDERSSON.
